Specification for Design.

Patented Sept. 6, 1921.

Application filed June 30, 1920. Serial No. 393,189. Term of patent 14 years.

To all whom it may concern:

Be it known that I, FLORA BENSON, a citizen of the United States, residing at Angleton, in the county of Brazoria and State of Texas, have invented a new, original, and ornamental Design for a Paper Doll, of which the following is a specification, reference being had to the accompanying drawing, forming part thereof, the same being a view of a goose with one style of dress thereon.

I claim:

The ornamental design for a paper-doll, as shown.

FLORA BENSON.
